POTATO SEED CUTTING MACHINE

Kenneth G. Brown, Mattituck, N. Y.

Application February 17, 1949, Serial No. 76,981.

2 Claims. (Cl. 146—163)

1

Broadly, my invention involves an improved machine for cutting certain vegetables, fruits, or the like, although in the present disclosure it is illustrated and described as being adaptable for potato seed cutting.

Heretofore, in machines of this specific type, no provision has been made for cutting a quantity of graded potatoes simultaneously, thus resulting in tedious and time consuming operation, as well as wear and tear on the machinery.

My invention overcomes this inherent drawback by providing means for cutting a plurality of potatoes of different sizes and shapes at one time. It consists, generally, of a frame upon which are mounted a suitable number of relatively long carriers in which are nested several graded potatoes, together with a bank of knives against which the carriers are advanced in such manner as to slice the potatoes into the desired number of parts.

In a more specific sense, my machine involves a rectangular frame supporting a pair of endless chains with gang carriers spanning the chains in spaced relationship, in combination with a bank of staggered knives disposed in the path of movement of the carriers. Each carrier has several pockets or recesses shaped to conform with the contour of small, medium, and large sized potatoes, and in turn, each pocket is provided with appropriate slots, depending upon the number of sections into which it is desired to cut the potatoes. The knives are disposed in alignment with the slots, and are fashioned to correspond with the contour thereof. It is deemed important in this connection, that the edges of the knives are slanted in echelon rearwardly from a longitudinal median line of the frame and that the knives which are subjected to the greatest frontal pressure, due to advance of the largest potatoes, are located forwardly of the bank, thus equalizing the pressure and making for a vertible slicing action of all potatoes in the carrier. Furthermore the slots of the pockets and knives are mated so that a plurality of potatoes of each grade are simultaneously sliced into their components.

To the accomplishment of the recited objects and others subordinate thereto, the preferred embodiment of my invention resides in the construction and arrangement of parts shown in the accompanying drawings, described in the following specification, and embraced within the scope of the appended claims.

In said drawings:

Fig. 1 is a top plan view of the machine embodying my invention, and

2

Fig. 2 is a side elevation thereof.

Fig. 3 is a transverse section along lines 3—3 of Fig. 1 illustrating one of the carriers, and Figs. 4 and 5 are a side elevation and end view, respectively, of one of the knives.

Referring more particularly to Figs. 1 and 2, 5 designates a rectangular frame having depending legs 6—7 braced by the intermediate longitudinally extending strut 8. At opposite extremities of the frame are pairs of sprockets 9—10, the former being carried at opposite ends of the shaft 11 and the latter being mounted on stub shafts 12. Shaft 11 is also provided with a gear wheel 13 which is connected with a motor 14 or any other suitable source of power by a chain 15. Trained over the two sets of sprockets 9—10 are endless chains 16—17 which, for the sake of protection, operate in their top reach directly beneath the longitudinal side members 18 of the 20 frame, and arranged transversely at spaced intervals between the chains are a plurality of carriers 19. As best shown in Fig. 3, each carrier consists of a relatively long bar 20 with sets of multiple companion pockets 21, 22 and 23 for holding graded potatoes. For example, pockets 21 are designed for small potatoes, as 24; pockets 22 for medium size potatoes 25; and pockets 23 for large size potatoes 26. And each set of pockets are slotted so that potatoes of different grades 25 will be sliced to produce the best results for seeds. Set 21 has a single vertical slot 27 whereby small potatoes may be cut in half; set 22 has a vertical slot 28 and an intersecting slot 29 extending horizontally in one direction, for cutting medium size 30 potatoes in three pieces; and set 23 has a vertical slot 30 and an intersecting horizontal slot 31 extending in two directions which is desirable for cutting large size potatoes into four parts.

Adjacent one extremity of the frame is suitably mounted an angular support 32. This support straddles the frame and has depending therefrom a plurality of pairs of knives, as 33, 34 and 35. Common to each knife is a horizontal head-plate 36 and a rearwardly slanted, vertically disposed blade 37 with a retreating cutting edge 38. And some knives, as 34 have, in addition, a single lateral blade 39, while other knives have lateral blades 40 extending in opposite directions, it being borne in mind that the disposition of the blade must conform to the shape of the slots in the pockets of the carriers as it is through these slots that the blades must pass as the carriers, loaded with potatoes, advance in their endless travel.

55 It will be further noted that the tandems of

knives are fixed in staggered relation and that the cutting edge of each blade is rearwardly inclined. It follows that as the potatoes of each grade are presented to the knives, the larger ones come first, the medium ones next, and the smaller ones last—all successively—and that each grade is sliced easily, smoothly and positively into the required number of sections.

In its broader aspects, my invention comprehends the employment, not only of various means described, but of equivalent means for performing the recited functions. By way of example, while not disclosed in the drawings, the frame and its accessories, instead of lying in a horizontal plane, may be placed in a vertical plane and operated with equal satisfaction. Also the number of pockets and knives may be increased or diminished at will. It is desired to reserve the right to effect such modifications and changes as may come fairly within the scope of the appended claims.

I claim:

1. A machine of the class described, comprising a rectangular frame, a pair of sprockets spaced apart for substantially the width of the frame and disposed near each end thereof, endless chains trained over each set of sprockets and operating adjacent opposite sides of the frame, a source of power for driving the sprockets, gang carriers arranged transversely and connected to the chains, each carrier consisting of a rigid, integral member including a plurality of contiguous pockets, the pockets being of graduated sizes, the smallest pocket having a single slot projecting outwardly of the carrier and the largest pocket having a pair of intersecting slots, a bank of knives at one end of the frame, the knife in the path of the smallest pocket comprising a single blade projecting inwardly toward the carrier, the knife in the path of the largest pocket having a blade projecting inwardly toward the carrier and a pair of laterally projecting blades, the pockets adapted to support small and large potatoes, and the carrier designed to be advanced against the knives, whereby, in a single operation, the potatoes are cut, according to their size, into two or four pieces.

2. A machine of the class described, comprising a rectangular frame, a pair of sprockets spaced apart for substantially the width of the frame and disposed near each end thereof, endless chains trained over each set of sprockets and operating adjacent opposite sides of the frame, a source of power for driving the sprockets, gang carriers arranged transversely and connected to the chains, each carrier consisting of a rigid, integral member including a plurality of contiguous pockets, the pockets being of graduated sizes, the smallest pocket having a single slot projecting outwardly of the carrier, the intermediate pocket having a single slot projecting outwardly of the carrier and a single laterally projecting slot and the largest pocket having a pair of intersecting slots, a bank of knives at one end of the frame, the knife in the path of the smallest pocket comprising a single blade projecting inwardly toward the carrier, the knife in the path of the intermediate pocket having a blade projecting inwardly of the carrier and a single laterally projecting blade, the knife in the path of the largest pocket having a blade projecting inwardly toward the carrier and a pair of laterally projecting blades, the pockets adapted to support small, medium and large potatoes, and the carrier designed to be advanced against the knives, whereby, in a single operation, the potatoes are cut, according to their size, into two, three or four pieces.
